UNITED STATES PATENT OFFICE.

GEORGE H. CHANDLER, OF PROVIDENCE, RHODE ISLAND.

BRACELET.

No. 826,086.

Specification of Letters Patent.

Patented July 17, 1906.

Application filed February 7, 1906. Serial No. 299,930.

To all whom it may concern:

Be it known that I, GEORGE H. CHANDLER, a citizen of the United States, residing at Providence, in the county of Providence, 5 State of Rhode Island, have invented certain new and useful Improvements in Bracelets, of which the following is a specification.

This invention aims to provide an improved bracelet, collar, or other band which 10 is extensible, so that its diameter may be increased or diminished. A bracelet of this sort, for example, may be passed over the hand and fit closely around the wrist, avoiding the necessity for a clasp and following 15 the contour of the wrist instead of being loose thereupon.

The particular features of novelty are specified in the claims hereinafter.

The accompanying drawings illustrate a 20 bracelet embodying the invention.

Figure 1 is a plan of one section of the bracelet. Fig. 2 is an elevation, partly in section, of the complete bracelet. Fig. 3 is a 25 sectional view of one of the parts of the bracelet. Fig. 4 is an enlarged detail of one end of an outer member of each section. Fig. 5 is an end view of the parts shown in Fig. 3.

Referring to the embodiment illustrated, the complete bracelet is made up of a number 30 of sections pivotally connected to each other, each section having an outer member and an inner member telescoping relatively to each other and connected by a spring, so as to permit the desired expansion. For example, each section may comprise an outer member A and an inner member B, these parts being of rectangular section, as shown, or of any suitable shape in transverse section. The rectangular shape shown prevents the 35 rotation of one part relatively to another. The parts may be made very conveniently of metal tubing. The part B fits closely within the part A, so that when extended in the manner shown in Fig. 3 it shall not appear to be of much smaller diameter than the part A, but shall appear rather as a continuation of the latter. The outer member A has an end plate C closing one end of it, while the inner member B has a similar end plate D closing 40 its opposite end. An inward flange E on the outer member engages an outward flange F of the inner member to prevent the latter from being pulled entirely out of the former. The end plate C is provided with a hook G on 45 its inner face and the end plate D with a similar hook H on its inner face. Eyes J and K

are provided on the outer faces of the end plates C and D, these eyes being of a shape to register with each other, so that a hinge-pin L may be passed through them. A spring 60 M connects the hooks G and H on the inner sides of the end plates C and D. The opposite ends of the member A are preferably arranged in radial directions or converging toward the center of the bracelet. The closed 65 end of the inner member B is similarly arranged. By this means the space between the successive sections of the bracelet is not substantially greater at the outer side than at the inner side, and the entire bracelet has 70 very closely the appearance of a true ellipse.

The bracelet may be decorated in various ways. The making of the top of the outer members A flat enables me to apply thereon a plate N, serving to receive a decoration of 75 precious stones or the like, as shown, and projecting slightly over the ends of the member, so as to conceal the pivotal joint.

In assembling the parts of the bracelet the part B may be inserted into the part A, the 80 end pieces C and D being not yet applied. The end plates C and D will then be connected to each other by means of the spring M, passed through the two members A and B, after which the end plates may be fastened 85 to their respective members either by soldering or otherwise. Preferably the end plates, as shown at C in Fig. 4, engage a shoulder O upon the end of the tubing of which each of the members is composed and are held in 90 place by swaging an edge P of the tubing over the preferably beveled edge of the end plate. This operation may be performed without heating, which might injure the temper of the fine spring necessary. It will be 95 seen, therefore, that the bracelet is made up of a number of separate sections each of which is complete in itself and each of which is connected to the next by an ordinary pin-hinge, so that the manufacture can be very 100 cheaply and rapidly carried on. Bracelets of larger or smaller size may be made by varying the number of sections or by increasing the size of the individual sections. Each spring is arranged to take only a certain and 105 equal portion of the expansion. There is no bending of the spring, but only a straight pull between its ends. The inner member B slides in the outer member A with a perfectly rectilinear movement. Preferably a stop Q 110 is provided by slightly punching in the inner face of the outer member A to restrict the

2
movement of the inner tube within the outer tube, so as to maintain the hinge-joints always entirely free. Each section is entirely independent in operation from the others.

5 Though I have described with great particularity of detail certain embodiments of my invention, yet it is not to be understood therefrom that the invention is limited to the specific embodiments disclosed.

10 Various modifications thereof in detail and in the arrangement and combination of the parts may be made by those skilled in the art without departure from the invention.

What I claim is—

15 1. An expandible bracelet or the like comprising a pair of members A and B, the latter telescoping into the former, a head C at one end of the member A, a head D at the opposite end of the member B, a spring M connecting said heads, and hinge members J and K upon the outer faces of said heads C and D.

20 2. An expandible bracelet or the like comprising a pair of members A and B, the latter telescoping into the former, a head C at one end of the member A, a head D at the opposite end of the member B, a spring M connecting said heads, and hinge members J and K upon the outer faces of said heads C and D,

said heads C and D being arranged in radial or converging directions.

3. An expandible bracelet or the like comprising a pair of members A and B, the latter telescoping into the former, a head C at one end of the member A, a head D at the opposite end of the member B, a spring M connecting said heads, and hinge members J and K upon the outer faces of said heads C and D, the member A being provided with a stop Q for limiting the inward movement of the member B.

4. An expandible bracelet or the like comprising a pair of members A and B, the latter telescoping into the former, a head C at one end of the member A, a head D at the opposite end of the member B, a spring M connecting said heads, hinge members J and K upon the outer faces of said heads C and D, and a plate N on the outer face of the member A and extending over the ends of the latter.

In witness whereof I have hereunto signed my name in the presence of two subscribing witnesses.

GEORGE H. CHANDLER.
